UNITED STATES PATENT OFFICE.

ALVIN O. OLAFSON, OF ST. PAUL, MINNESOTA.

RAZOR STROPPER.

Application filed March 13, 1926. Serial No. 94,419.

My invention relates to stroppers, the primary object of which is to provide a stropper for razor blades which may be held in a compact case or inclosure so as to completely inclose the razor blade while it is being stropped and to protect the operator of the stropper.

A feature of the invention resides in providing a stropper made of sheet material having a comparatively uniform thickness throughout its construction and made from stampings cut by dies. Parts of the stropper are associated together to provide a simple yet very effective stropper having a design which is adapted to entirely inclose the razor blade in operation and to permit the blade to be stropped on two edges at one time, thus adapting my stropper to two-edged razor blades or to a single edged blade so as to thoroughly strop and sharpen the blade in a rapid and a simple, yet very effective manner.

It is also a feature of my invention to provide a stropper wherein the razor blade is automatically lifted in opening the stropper so that the blade is held elevated in a manner so that it may be easily engaged and lifted from the stropper. This is an important feature of my invention as it permits the blade to be readily removed or placed in the stropper.

The invention includes a razor stropper having means adapted to open automatically by releasing one end of the stropping member and pulling on the other end, which operation automatically releases the catch means which holds the case of the stropper closed.

A further feature of importance in my invention resides in means of construction whereby when the stropper is automatically opened by pulling on one end of the strop with the other end released, the razor blade is automatically elevated and held in a disengaged position clear of the sides of the stropper case so that it may be easily engaged.

My stropper is designed to have a very small compact nature so that it can be folded together into a very small package and in fact, can be contained in a vest pocket case with the razor blade held and protected with-

in the same, thereby providing a very desirable stropping means which can be easily carried. The parts of my stropper are designed to fulfill the feature of compactness which I have desired to accomplish in making my stropper.

An important feature of my invention resides in the means adapted to automatically open the stropper case by pulling on one end of the strap and simultaneous with the opening, the elevating of the razor blade and holding the blade in elevated position so that the blade may be easily engaged, and thus permitting a razor blade to be readily inserted or removed from my stropper.

It is also an object of my invention to provide a stropper having particular means of supporting the same so that in folding the stropper, it may be readily laid flat, yet having a construction which can be attached to a hook readily and the ends of the strap engaged to pull the same back and forth to thoroughly and quickly strop the razor blade. My stropper also includes a particular means of engaging the blade to support the same within the strop, this means including the receiving plate upon which the blade rests, resilient means for centering the receiving plate, and a clamping or closing plate which co-acts with the blade receiving plate. By this construction I provide an extremely simple stropper which is particularly adapted to thin double-edged blades. All of these parts are completely encased within the member which are hingedly connected together and adapted to be automatically opened when it is desired to remove or place a blade within the stropper.

These features and objects, together with other particular details of construction will be more fully and completely set forth in the following specification and claims.

In the drawings forming part of this specification:

Figure 1 is a perspective view of my stropper as it would appear in use.

Figure 2 is a side view of the same.

Figure 3 is a front view of a portion of the case of the stropper in open position.

Figure 4 is a side view of the stropper with the case in open position.

Figure 5 is a perspective bottom view of the stropper case, the strap portion being broken away.

Figure 6 is a detail of a portion of my stropper.

Figure 7 is a side view of a detail portion of my stropper.

Figure 8 is a perspective of a detail portion of my stropper.

10 Figure 9 is a perspective of one of the sides of the case of my stropper.

Figure 10 is a plan view of the blade receiving plate which is used in my stropper for single edge blades.

15 Figure 11 is a front view of the plate illustrated in Figure 10.

Figure 12 illustrates the blade holding member for the single edge blade.

In the drawings my stropper A is formed 20 in a manner to provide a very compact case B which is formed with an upper case member 10 and a lower case member 11 which are hingedly connected together at 12.

25 The case B of my stropper A is designed to provide means for receiving a razor blade, either of the double or single edge type, and the stropper is designed to hold the razor blade when not desired for use within the stropper case B. The stropping strap C is 30 connected to the case by passing through the slot 13 in the flange 14 formed on the free end of the cover member 10 and beneath the transverse rib member 15 extending across the top portion 10 adjacent the flange 14. This rib member is provided to hold the stropping strap in close proximity to the blade within 35 the stropping case B. The strap then extends about the tubular member 16 which is positioned on the pin 17 and holds the case members 10 and 11 pivotally connected together at 40 12. The strap then extends from the member 16 along the inside of the bottom case member 11 and over the rib 18 and out through the slot 19 formed in the upwardly projecting flange 45 20 formed on the free end of the bottom member 11 of the case B. When the case B is in closed position the flanges 14 and 20 meet so as to form a closure along the free end of 50 the case members and through which the strap C passes.

The strap C is formed with suitable engaging handles 22 on either end which are adapted to be engaged to draw the strap back and forth through the case B.

55 A pair of side arms 25 are pivotally supported through the opening 26 to attach the same at the pivot point 12 on one end, while the other end is formed with an offset end portion 27 from which the portion 28 extends approximately at right angles to the portion 27, and from the portion 28 the portion 29 is bent to extend approximately at right angles to the portion 28. Thus the portions 27 and 29 are extended approximately parallel to each

other, thereby providing an offset supporting 65 bracket arm on the free end of the arm 25.

There are two arms 25 in my stropp A, one being positioned on each side of the case B, as illustrated in Figure 1 of the drawings and in Figure 3. The portion 29 is adapted to extend through the slots 30 formed in the cover 10 of the case B and by means of the lug 31 the portion 29 engages beneath the inside of the cover 10, as illustrated in Figure 4. Thus the lugs 31 form an engagement with the inside 70 of the cover 10 to hold the free end of the arm 25 firmly connected to the free end of the cover 10. Adjacent the lugs 31 I provide short lugs 32 which are adapted to support 75 one end of the coil springs 33. The other end of the coil springs 33 engage over the lugs 34 formed on the depending flange 14 of the cover 10, as clearly illustrated in Figure 9 and also illustrated in Figure 4.

The cover 10 is formed with depending ears 85 35 on either side of the same in which I provide slots 36 which are adapted to engage over the pin 12 to pivotally and slidably support the cover 10 at the pivot point or rod 12. At the back of the cover an arcuated skirt 37 is provided to close the back of the case B and to provide a neat and smooth construction to the stropper case. On the free end of the cover 10 I provide projecting shoulders 38 on either 90 side of the same which are adapted to engage beneath the hooks 39 in a manner to attach the cover 10 to the bottom 11. The hooks 39 are formed on the upwardly projecting side walls 95 of the cover 11.

In opening and closing the case of my 100 stropper A it is only necessary to engage that portion of the strap C which extends through the bottom 11 and through the flange 20 out through the slot 19, and pull the same sufficiently to cause the attaching portion of the handle 22 to strike against the flange 14 of the cover 10, which causes the springs 33 to be compressed, and by means of the slots 36 the cover 10 is adapted to slide backward sufficiently to release the lugs or shoulders 38 110 from the hooks 39, whereupon the cover 10 automatically opens by reason of the pull strap. In this manner I provide a stropper case B which automatically opens by pulling on one end of the strap C.

115 The case B is adapted to conceal the razor blade E which is illustrated in dotted outline in Figure 6, so that when the stropper A is in use, the razor blade is entirely concealed and protected within the case B. I provide razor blade supporting arms 40 which are rigidly secured to the ends of the sleeve 16 and which are formed with arcuated lugs 41 on one end of the same, while the free end 42 is formed with a bifurcated end to provide lugs 43 adapted to receive the razor blade supporting plate 45. The razor blade supporting plate 45 is adapted to fit freely be-

tween the lugs 43 so that it can oscillate back and forth between the lugs 43 freely in operation. The razor blade supporting plate 45 is formed with a pair of short lugs 46 extending from each side of the same which are adapted to be engaged by the ends of the springs 47 carried by the pivot member 12. The springs 47 are provided with arms 48 and 49, the arm 49 being formed with a hook 50 which extends over the end 51 of the arm 48. The arm 48 extends on one side of the lugs 46, while the arm 49 extends on the other side, and the lugs 46 are formed with an upwardly bent end which extends at right angles to the plate 45 so that the spring arms 48 and 49 are held in a manner to engage on either side of the plate 45 and to prevent disengagement of the free ends of the spring 47 from the plate 45. The springs 45 function to hold the plate 45 normally parallel with the sides of the case 10 and 11. These springs 47 are very sensitive in action and tend to move the razor blade supporting plate 45 parallel with the sides of the strap 25 C as quick as pressure or pull is released from the ends of the strap, thus preventing cutting of the strap in stropping.

The plate 45 is formed with a pair of long lugs 52 which are adapted to extend beyond the lugs 46 and engage in the slots 53 in the side walls of the bottom 11 when the case B is closed.

The plate 45 is of a flat, thin construction and is provided with blade engaging lugs 54 which project upwardly from the same so as to engage in the holes of the blade E. A recess 55 is formed on the front of the plate 54 to permit free engagement of the blade E to remove the same from the plate 45.

40 A blade clamping plate 56 is freely pivoted at the opening 57 in the sides of the arms 25. The clamping plate 56 is of a simple, flat nature and is freely disposed in the openings 57 so that it will pivot readily to adjust itself with the blade carrying plate 45. When the cover 10 is closed, the plate 56 bears down against the plate 45 in a manner to clamp the razor blade between the two plates.

In stropping the blade E, the blade is placed on the plate 45 when the same is held in the elevated position illustrated in Figure 4. The lugs 41 function to cause the opening of the case B to raise the plate 45 by causing the arms 40 to be centered between the sides 10 and 11 of the case B. This holds the plate 45 elevated when the case is open and permits the blade to be easily engaged to remove it or to fit the same on the plate. When the case is closed the plate 56 engages and clamps the blade to the plate 45.

In stropping, the ends 22 of the stropper are engaged and by means of the holding loop 60 which is formed with hook ends 61 to freely pivot the loop 60 to a pair of ears 62 which are riveted to the end of the pivot rod

12 so that the ears 61 will pivot freely at the pivot point or rod 12, the strap C can be pulled back and forth by engaging in the hand loops 22, and cause the strap C to slide over the member 16 causing friction to move the 70 arms 40 toward either side of the strap C. As the arms 40 move toward the strap in the direction of the pull, the razor supporting plate 45 is adapted to adjust itself in a manner to permit the cutting edges of the blade E to 75 bear against the strap and thus automatically strop the blade, the springs 47 moving the blade to neutral position the moment that the stropping ceases. As the ends of the strap C are pulled back and forth the blade E is reciprocated from one side to the other to strop the cutting edges on both sides. In this form of blade as illustrated by the dotted outline as the razor blade E, the double cutting edge is provided and the plate 45 together with 80 the clamping plate 56 will permit the razor blade to move back and forth to freely strop the cutting edges.

When the stropping operation is complete, it is only necessary to pull on one of the handles 22 and release the other end of the strap C so that it will pull against the free end of the cover 10. Thereupon the case B automatically opens and the razor blade E is elevated automatically into the position of the 95 arm 40 in Figure 4. The operation of my stropper A is very simple, yet it is effective, and the neat compact construction is very desirable for a stropper of this nature. The holding loop 60 can be folded over on to the 100 case as illustrated in Figure 5, and the ends of the strap C can be folded about the case B, thus forming a very compact stropper A, with the razor blade E held and protected within the same and permitting the stropper 105 to be packed into a very compact state when not being used. Nevertheless, the strop is ready for use at any time and by engaging the holding loop 60 over a hook on the wall, the ends 22 can be engaged and in a few 110 moments the razor blade E stropped thoroughly and the stropper A automatically opened by pulling on one of the handles.

By means of the blade receiving plate 65 illustrated in Figures 10 and 11, a razor 115 blade with a single cutting edge, such as is illustrated in dotted outline in Figure 10, can be stropped readily in my stropper A. The razor blade F in this holding means is held on the plate 65 sliding beneath the ears 66 and being clamped by the clamping bar 67. The clamping bar 67 is supported at the pivot point 57 in the arms 25, while the plate 65 is supported by the arms 40. This blade holding means in Figures 10, 11 and 12, functions just the same as that heretofore described, excepting that it is adapted to hold a single edge blade. Therefore, it is readily apparent that my stropper A is adapted for different razor blades.

It is an essential feature of my invention, however, to provide a razor strop of simplicity, compactness and of an automatic nature, so that the cover snaps into locking 5 position automatically, and also opens automatically by pulling on one end of the strap, and the blade is adapted to be self-centering automatically by the spring means provided to hold the same against cutting the 10 strap. The feature of elevating the blade is also of importance as it permits the blade to be readily engaged or placed within the strop A.

In accordance with the patent statutes I 15 have described the principles of operation of my razor strop A and while I have illustrated a particular formation and construction of the same, I desire to have it understood that the same is only illustrative and 20 that other forms of my invention can be adapted for the purposes set forth within the scope of the following claims.

I claim:

1. A razor strop including, a casing 25 having a compact nature with side walls so mounted as to swing open and adapted to close approximately parallel to each other, means for supporting a razor blade between said side walls, a razor strop, means for receiving and guiding said razor strop between the side walls in a manner so as to strop the blade held therebetween, and said razor strop being so disposed in said casing as to open 30 said casing by pulling on one end of said strop in a direct lengthwise pull of the strop. 35

2. A razor strop including a casing capable of being opened, means for supporting a razor blade within the casing, a stropping member and means for moving the razor 40 blade, said stropping member being so disposed in said casing as to open said casing and operate said razor blade moving means upon a pull upon one end of said stropping member in a direct lengthwise direction.

3. A razor strop including, a casing capable of being opened, means for supporting a razor blade within said casing, means to raise the razor blade from one side of the casing when the casing is opened and a stropping member so disposed in said casing as to open said casing by a direct lengthwise pull of said stropping member. 50

4. A razor strop comprising a blade holder, a casing having a thin, flat, compact 55 nature with approximately parallelly extending side walls, one of said walls forming the cover and the other the bottom, means for pivotally supporting said walls together so that the casing may be opened, means for locking the free ends of said walls to entirely close said casing and a strop in said casing so disposed as to open said casing by a direct lengthwise pull of the strop in said casing. 60

5. A razor strop including a blade holder, a strop adapted to be reciprocated back 65

and forth by engaging the ends thereof, a compact, flat, thin case having a cover and bottom portion hingedly secured together so that the case may be opened and said strop being so disposed in said case as to open said case by pulling on the strop in a direct lengthwise pull. 70

6. A strop for a razor blade including a blade holder, a supporting bail, a casing having a flat, thin, compact construction capable of being opened and adapted to entirely inclose the razor blade, means for locking said casing in closed position, and a stropping member positioned in said casing for opening said casing by a direct lengthwise pull upon the strop and simultaneously exposing, releasing and elevating the razor blade with the opening of said casing. 75

7. A strop for razor blades having a blade holder, a casing adapted to inclose the razor blade, said casing being of a compact, thin nature and provided with two members hingedly connected at one end thereof so that the casing may be opened, means for locking the free ends of said casing together, a razor stropping member disposed in said casing, one of said casing members being slidable in a manner to permit the opening of said casing by a direct lengthwise pull of the razor stropping member. 80

8. A razor strop comprising a stropping member, a blade holder, a casing adapted to entirely inclose a razor blade while being stropped, said casing including members hingedly and slidably connected so that the casing can be opened, the side walls of said members being positioned in close proximity to each other to form a thin, compact casing with practically only sufficient space between the sides of said casing to receive a razor blade 90 and the thickness of said stropping member and said stropping member being so positioned in said casing as to open said casing by a direct lengthwise pull of said stropping member and releasing and elevating the razor 95 blade simultaneously with the opening. 100

9. A razor strop including, a casing having two members hingedly connected together so that the casing can be opened, one of said members forming the cover and the other member forming the bottom portion to provide a case for inclosing the razor blade when being stropped, a razor stropping member extending through said members and extending out of the free ends of the same, means for receiving a razor blade, means for clamping the razor blade when said members are moved into closed position, and said stropping member being so disposed in said casing as to elevate, release and expose the razor 115 blade by a direct lengthwise pull of said stropping member. 120

10. A strop including, a casing having a pair of members, means for pivotally supporting said members in a manner to lie ap- 130

proximately parallel to each other and so that the casing might be opened, a stropping member extending into said members, means for locking said members together, means for supporting a razor blade between said members in a manner so as to cause the same to oscillate back and forth to strop the same, means for holding the razor blade clamped in said casing against longitudinal movement, and said stropping member being so disposed in said casing as to unlock said casing members and open the same to expose the razor blade by pulling on the stropping member in a direct lengthwise pull.

11. A stropper including, a casing capable of being opened, means for holding a razor blade in said casing, a stropping member, said holding means being capable of be-

ing oscillated by said stropping member, and said stropping member being so positioned in said casing as to open said casing to allow removal or insertion of a razor blade by pulling one end of the stropping member in a direct lengthwise pull.

12. A stropper including a casing so mounted as to be capable of being opened and closed, a stropping member disposed within said casing, razor blade holding means positioned in said casing, said stropping member being so disposed in said casing as to open said casing by pulling on one end of said stropping member in a direct lengthwise pull in order to expose said razor blade holding means.

ALVIN O. OLAFSON.
